UNITED STATES PATENT OFFICE.

LEON W. CAMPBELL, OF PROVIDENCE, RHODE ISLAND.

FILER FOR ROVING FRAMES.

1,420,966.

Specification of Letters Patent. Patented June 27, 1922.

Application filed May 2, 1919. Serial No. 294,317.

To all whom it may concern:

Be it known that I, LEON W. CAMPBELL, a citizen of the United States, residing at Providence, in the county of Providence, State 5 of Rhode Island, have invented certain new and useful Improvements in Fliers for Roving Frames, of which the following is a specification.

My invention is an improved flier for roving-frames or like textile apparatus. The object of my improvement is to provide means for controlling the action of the presser which winds the roving on the bobbin, whereby a more constant and uniform 10 tension is maintained on the strand to insure a more even and level yarn in the finished product. A further object of the improvement is to provide a simpler and more convenient method of threading the flier 15 with the roving strand, and in general to render the device easier to operate and more efficient in use.

The manner and means for carrying out these improvements are fully described in 20 the following specification, illustrated by the accompanying drawings, in which like reference characters designate like parts. In the drawings:

Fig. 1 is a side elevation of my improved 25 flier shown in connection with the bobbin on which it operates;

Fig. 2 is an enlarged, vertical-sectional 30 view of the upper portion of the flier, showing the controlling means for the presser;

Fig. 3 is a plan view of the same in part 35 section on the line X—X of Fig. 2;

Fig. 4 is a view similar to Fig. 2, showing a modification in the structure of the 40 presser-rod and its mounting; and

Fig. 5 is a detail view showing a modified 45 arrangement of the connection between the presser and its controlling-arm.

Referring first to Fig. 1, S designates the 50 vertical spindle for rotating the flier F supported on its upper end, and A is the bolster which carries the bobbin B on which the roving is wound. The bolster A is provided with a tubular sleeve 2 surrounding the spindle S and fitted to the bore of the wooden 55 bobbin B which rotates thereon in coaxial relation with the spindle S. At the lower end of the sleeve 2 is a rotatable bushing 3 provided with a bevel-gear 4 through which it is connected to be driven from the operating mechanism of the machine. At the upper end of the bushing 3 is a flange or collar

5 having a lug or spur 6 adapted to engage notches 7 in the base of the bobbin B to connect the latter rotatively therewith. The bolster A is connected to the rail of the roving-frame by an arm 7, whereby it may be reciprocated up and down to impart the rising and falling motion to the bobbin in relation to the flier; these connections not being herein illustrated or described in detail as 60 they form no part of the present invention, but are of usual construction as well known to those versed in the art.

Referring now particularly to Figs. 2 and 3, the upper end of the spindle S is reduced 70 in diameter at 9 and fitted to its periphery is a tubular sleeve 10 which serves as the mounting or support for the flier F. Extending across the interior of the sleeve 10 is a pin 11 adapted to engage a cross-slot 12 75 in the top of the spindle S, whereby to key the flier F rotatively therewith while allowing for its removal therefrom for placing the bobbin B on, or doffing it from, the bolster A. The sleeve 10 is provided at its upper end with radial arms 14—15 which are bordered by upstanding, marginal flanges 16, forming a shallow box or casing C which takes somewhat the shape of a semaphore arm. The sides of the right-hand arm 15 80 taper inwardly, as shown in Fig. 3, and terminate in a tubular sleeve 17 which projects downwardly to form a bearing or mounting for the upper end of the vertical presser-rod or shaft 18, see Figs. 1 and 2. As shown in 85 Fig. 2, the rod 18 has a cylindrical hub or head 19 at its upper end formed with an annular groove 20 at the bottom and a beveled edge 21 on its top. The head 19 is adapted to fit within the bearing-sleeve 17 with series 90 of anti-friction balls 22—23 at its ends. The groove 20 at the bottom of the head 19 forms a race for the lower set of balls 23 which bear against a concaved shoulder at the bottom of the sleeve 17; while the upper 95 balls 22 bear against the beveled edge 21 of the head 19 and are held in place by a cap 24 screwed into the top of the sleeve. The cap 24 is adjusted in place to permit a free 100 rolling motion of the balls 22—23 as the head 19 rotates in its bearing while preventing axial movement of the rod 18. The rod 18 extends downwardly from its bearing in parallel, spaced relation with the bolster sleeve 2 and is preferably reduced in thickness or cut away on one side to lighten its 105 structure. As illustrated by the dotted lines

in Fig. 3, the rod 18 is made half-round in cross section and is hollowed or concaved along its side to provide a groove or channel 30 for the strand R to draw through. 5 At the top and bottom of the rod 18 are hook-like guides 31—31 for retaining the strand in place; while at its lower end the rod is bent at right-angles to form the presser-arm 32. At its outer end the arm 32 10 is flattened to form the presser-foot 33 which bears against the bobbin as the strand of roving is wound thereon. In the center of the presser-foot 33 is a guide-eye 34 having a restricted opening on its side through which 15 the strand is entered. One side of the head 19 of the presser-rod 18 is cut or milled with a series of longitudinal grooves forming gear-teeth 35, see Fig. 3, which are adapted to mesh with a toothed sector 36 on the end 20 of a counterweight-lever or presser-controller 37.

The presser-controller or weight-lever 37 is arranged in horizontal position within the casing C with its toothed end inserted 25 through an opening 39 on the side of the bearing-sleeve 17, see Fig. 2. On the opposite end of the lever 37 is a disk-like weight 40, and intermediate its extremities is an enlarged hub 41 having a relatively large 30 bore 42.

Fitted to the top of the casing C is a flat cover C' formed with an upstanding tubular thimble 43 arranged concentric with and forming an extension of the sleeve 10 which 35 supports the flier on the spindle S. The thimble 43 is provided with an opening 44 in its top and an aperture 45 on its side through which the strand of roving R is led in the manner illustrated in Fig. 1. On the 40 side of the arm 15 is a pin 46 across which the strand R draws as it leads to the presser-rod 18, the strand being guided along the latter in the manner as later explained. The cover C' is fastened in place on the top of 45 the casing C by means of screws 47 and on its under side is an enlarged hub 48 disposed eccentric to the axis of the spindle S. Referring to Fig. 2, the hub 48 enters the bore 42 in the counterweight-lever 37 and 50 serves as a bearing therefor to pivot the lever on an axis eccentric to the axis of revolution of the flier F. Normally, as the flier F rotates about the axis of the spindle S, centrifugal force will tend to maintain the 55 weight-arm 37 in mean position, as illustrated in Fig. 3. The lever 37 is swung out of this position by the turning of the rod 18 in its bearing under the influence of the presser-foot 33 as the latter is forced radially outward from the axis of the bobbin B by the growth of the winding building up thereon. The method of operation of the 60 complete apparatus is as next explained:

In preparing the machine for operation 65 the flier F is lifted off from the spindle S

and a wooden bobbin or shell B slipped onto the bolster tube 2 with one of the notches b at its base engaged with the driving lug 6. The flier F is then replaced on the spindle S with its cross-pin 11 engaging 70 the slot 12 in the end of the spindle to provide a driving-connection therebetween. The strand of roving R, represented by dot-and-dash lines in Fig. 1, is led down from the drawing-rolls through the opening 44 in 75 the thimble 43 on the cover C', thence out through the aperture 45 on its side, and after being given a partial wrap there-around is carried across the guide-pin 46 to the presser-rod 18. From the pin 46 the 80 strand R passes over the upper guide-hook 31, thence through the channel 30 in the rod 18 and under the lower hook 31 to the presser-foot 33. As the strand leaves the 85 guide 31 it is wrapped around the arm 32, then led through the guide-eye 34 and its 90 end secured to the bobbin B by giving it a few turns therearound. The roving-frame is now started to operate to rotate the spindle S and bolster-sleeve 2, the latter being 95 driven at a faster rate than the spindle and at a gradually accelerated speed in the manner as well known to those versed in the art. The bolster-sleeve 2 will thus be rotated in advance of the flier F and as the bolster 100 A rises and falls in relation to the presser 33 the latter is caused to traverse the roving longitudinally of the bobbin B to deposit it in layers thereon. As the strand R leads down through the thimble 43 and there-around to the rod 18, thence around the arm 32 and through the guide-eye 34 in the presser 33, a slight resistance is applied to its draft to provide the required tension. The turning of the bobbin in advance of the 105 flier gives the twist to the roving as it winds thereon, and as the bobbin increases in diameter its rotation is accelerated to preserve a constant ratio between its peripheral speed and the speed of the flier. 110

Referring to Fig. 3 of the drawings, at the start of the winding operation the presser-foot 33 bears against the barrel of the bobbin B as represented by full lines in this view. Now, as the successive layers of roving 115 are laid in place the presser will be gradually swung outward from the axis of the bobbin until, when the winding reaches its full diameter, it will have been carried into the position indicated by dash lines in 120 Fig. 3. This swinging movement of the presser-arm 32 acts through the rod or shaft 18 to turn the toothed head 19 in its bearing 17, and the motion of the latter is communicated through the gear-sector 36 to swing 125 the counterweight-lever 37 toward the position shown by dotted lines in Fig. 3. It has before been explained that during the rotation of the flier F the action of centrifugal force tends to maintain the weighted lever 130

37 in mean position, due to the fact that its axis is offset or eccentrically disposed in relation to the axis of revolution to the flier. Consequently, the displacement or swinging-movement of the weight-lever 37 is resisted to some extent, in proportion to the size of the weight at its end, and hence the turning movement of the shaft 18 is likewise resisted. This action tends to maintain the 10 presser-foot 33 constantly bearing on the periphery of the mass of roving as it builds up on the bobbin B to provide the required pressure thereagainst. It is also to be noted that since the displacement of the counter-weight-lever 37 is so slight the resistance or 15 drag which it applies to the presser remains substantially constant throughout the full movement of the latter. That is to say, as the presser-foot 33 moves outwardly from 20 the axis of the bobbin its pressure on the roving is not increased to any appreciable extent, and therefore a more constant and uniform tension is applied to the strand from start to finish of the winding on process.

Fig. 5 illustrates a modification in the arrangement for connecting the presser-rod or shaft 18' to swing the counterweight-lever 37'. In this embodiment of the device the 30 head 19' of the shaft or rod 18' is provided with a single tooth or projection 50 which engages a notch or opening 51 in the end of the arm 37'. This construction is somewhat simpler than the arrangement shown 35 in Figs. 1 and 2 and obviates the necessity of cutting gear teeth on the head 19'. The method of operation of this form of the mechanism is substantially the same, however, as that previously described and it is 40 obvious that other modifications could be made in the method of interconnecting the parts without departing from the principle of their operation.

Fig. 4 shows another arrangement of the 45 presser-rod and its mounting as modified from the construction shown in Fig. 2. In this embodiment the presser-rod or shaft 52 is made tubular and provided with a flange 53 at the lower end of its enlarged 50 hub or bearing-head 54. Fitted to the bore of the bearing-sleeve 17 is a bushing 55, preferably constructed of impregnated wood to provide what is known in the mechanical arts as an "oilless" bearing. The head 54 of 55 the rod 52 is fitted to turn in the bore of the bushing 55 with its flange 53 abutting the lower end thereof, and a pin 56 driven through the side of the bearing-sleeve 17 engages with a peripheral groove 57 in the 60 head to hold it in place. Cut through the side of the bearing 17 and bushing 55 is a vertical slot 58 which registers with a corresponding slot 59 in the head 54. The slot 59 is continued downwardly through the 65 side of the tubular rod 52 and is twisted

spirally therearound as shown at 60. Mounted on the lower end of the rod 52 is the presser-arm 61 terminating in the presser-foot 62 formed with a guide-eye 63. The object of this arrangement is to provide for 70 easier threading of the flier in leading the strand of roving through its guideways. With this construction the strand is led from the thimble 43 on the cover C' to the outside of the bearing sleeve 17 and then 75 drawn down through the slots 58-59 to enter it in the bore of the head 54. By giving the strand a wrap around the rod 52 it can then be entered through the spiral slot 60 into the longitudinal bore of the rod 52. 80 From the bottom of the rod 52 the strand R is led around the presser-arm 61 and thence through the guide-eye 63 in the presser-foot 62. It will thus be seen that the rod 53 may be threaded with the strand R 85 with a few simple movements of the hand, tending to make for greater ease and convenience in preparing the flier for operation.

My improved device provides an extremely simple and efficient apparatus having but few parts which are proof against derangement or damage under severe conditions of use. The elements of the flier are properly balanced to provide for high speed 90 operation and the novel arrangement of the controlling-means for the presser provides for a more constant and even tension on the strand of roving as it delivers to the bobbin. For this reason a more uniform twist is applied to the strand and the bobbin builds up 95 with a more perfect formation, whereby the roving delivers more freely and evenly in unwinding, resulting in a more even and level yarn in the finished product. 100

Various modifications other than those herein shown might be made in the structure and arrangement of the parts of the device without departing from the spirit or scope of the invention; therefore, without 110 limiting myself to the precise embodiment illustrated, what I claim is:

1. In a flier for roving-frames or like textile apparatus, the combination with a member rotatable about the axis of the roving-bobbin, of a presser hinged to said member on an axis parallel with and at a distance apart from the axis of the bobbin, a weighted lever pivoted on a separate axis from that of the presser and eccentrically disposed with relation to the axis of the bobbin, and means connecting the presser to the weighted lever to swing the latter against the resistance applied thereto under the action of centrifugal force. 115

2. In a flier for roving-frames or like textile apparatus, the combination with a member rotatable about the axis of the roving-bobbin, of a presser hinged to said member to adapt it to bear against the rov- 120

ing as it winds onto the bobbin, a counter-weight-lever pivoted on a separate axis from that of the presser and disposed in eccentric relation to the axis of the bobbin, 5 and gearing connecting the presser with the counterweight-lever to move the latter as the presser swings outwardly with the growth in the winding.

3. In a flier for roving-frames or like 10 textile apparatus, the combination with a supporting-member rotatable on the axis of the roving bobbin, of a presser-rod journaled in a bearing on said member, a presser on said rod adapted to bear against the 15 roving as it winds onto the bobbin, a weighted lever pivoted on the supporting-member on an axis separate from that of the presser-rod and disposed in eccentric relation to the axis of the bobbin, and 20 means on the presser-rod engaging the weighted lever to swing the latter against the action of centrifugal force as the presser recedes from the axis of the bobbin with the growth in the winding.
- 25 4. In a flier for roving-frames or like textile apparatus, the combination with a member rotatable on the axis of the roving-bobbin, of a presser pivoted on said member to adapt it to swing outwardly from the 30 axis of the bobbin as the roving is wound thereon, a counterweight-lever pivoted on the member on a separate axis from that of the presser and disposed in eccentric relation to the axis of the bobbin, and means 35 intermediate the presser and counterweight-lever for imparting movement to the latter against the action of centrifugal force whereby to apply a constant resistance to the movement of the presser throughout the 40 building of the bobbin.

5. In a flier for roving-frames or like apparatus, the combination with the bolster for supporting and rotating the bobbin, of a radial-arm rotatable about the axis of the 45 bobbin independently thereof, a bearing at the end of said arm, a rod journaled in said bearing in parallel spaced relation with the axis of the bobbin, a presser carried by said rod to adapt it to bear against the bobbin 50 and to swing away from its axis during the winding, a weighted lever pivoted on the arm in eccentric relation to its axis of rotation, and means connecting the lever to be swung from the turning of the presser- 55 rod in its bearing as the presser recedes from the axis of the bobbin with the growth in the winding.

6. In a flier for roving-frames, the combination with a rotating spindle, of a member 60 supported on said spindle and rotated thereby, a rod journaled in a bearing on said member and extending in parallel relation with the spindle, a presser at the lower end of the rod adapted to bear against the bobbin being wound, a counterweight-lever piv-

oted on a separate axis from that of the presser-rod and disposed eccentric to the axis of the spindle, and means connecting the presser-rod to the counterweight-lever to swing the latter against the action of centrifugal force as the presser recedes from the axis of the bobbin with the growth of the winding. 70

7. In a flier for roving-frames, the combination with a rotatable-member formed with a radial arm having a bearing at its end, of a rod journaled in said bearing in parallel relation to the axis of rotation of the member, a presser on said rod adapted to bear against the bobbin being wound, a weighted lever pivoted on the member in eccentric relation to its axis of rotation, and means connecting the rod to swing the lever against the action of centrifugal force as the member is rotated on its axis. 75

8. In a flier for roving-frames, the combination with a rotatable member formed with a radial arm having a bearing at its end, of a rod journaled in said bearing and formed with gear teeth on its side, a presser carried by said rod to adapt it to bear against the bobbin being wound, and a weighted lever pivoted on the arm-member in eccentric relation to its axis of rotation, said lever formed with gear teeth at its end engaging the teeth on the presser-rod to adapt it to be moved therefrom against the action of centrifugal force. 90 95

9. In a flier for roving-frames, the combination with a member having a radial arm formed with a bearing at its end and a hub at its center disposed in eccentric relation to its axis of rotation, of a rod journaled in the end-bearing of the arm, a presser carried by said rod to adapt it to bear against the bobbin being wound, a weighted lever pivoted on the eccentric hub of the arm, and means connecting the presser-rod and weighted lever to swing the latter against the action of centrifugal force as the flier rotates about the bobbin. 100 105

10. In a flier for roving-frames, the combination with a rotatable spindle, of a member fitted to the end of the spindle and formed with opposite radial arms having marginal flanges to provide a shallow casing, a bearing at the end of one of the arms, a rod journaled in said bearing, a presser on the end of the rod adapted to bear against the bobbin being wound, a weighted lever pivoted within the casing on an offset hub disposed eccentric to the axis of the spindle, means connecting the rod with the weighted lever to adapt the latter to be moved from the turning movement of the rod under the action of the presser, and a cover fastened to the top of the casing to hold the lever in place and protect the parts from dust and lint. 115 120 125

11. In a flier for roving-frames, the com- 130
